DESIGN FOR A COOKING STOVE

Carl C. H. Rasmussen, Silver Spring, Md.

Application March 24, 1945, Serial No. 118,666

Term of patent 3½ years

(Cl. D81—10)

To all whom it may concern:

Be it known that I, Carl C. H. Rasmussen, a citizen of the United States, residing at Silver Spring, county of Montgomery, State of Maryland, have invented a new, original, and ornamental Design for a Cooking Stove, of which the following is a specification, reference being had to the accompanying drawing, forming a part thereof.

The side of the cooking stove not shown in the perspective view Figure 1 is substantially like the side shown.

I claim:

The ornamental design for a cooking stove, as shown and described.

CARL C. H. RASMUSSEN.
